W. BIXBY

YARN SPOOL

Filed Sept. 10, 1923

Inventor:
Walter Bixby
by
J. W. N. Yodlurd, Atty.

UNITED STATES PATENT OFFICE.

WALTER BIXBY, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

YARN SPOOL.

Application filed September 10, 1923. Serial No. 661,805.

To all whom it may concern:

Be it known that I, WALTER BIXBY, a citizen of the United States, and resident of Boston, in the county of Suffolk and State 5 of Massachusetts, have invented certain new and useful Improvements in Yarn Spools, of which the following is a specification.

This invention relates to yarn spool and particularly to spools for use in tube frames 10 for tuft weaving, and is intended to provide a simple, durable and rigid construction for holding and delivering of the yarn as required.

According to prevailing practice such 15 spools are made of a solid wooden roll to which are glued or pinned end heads or disks to form exterior retaining flanges for the yarn, but such spool construction unless made by expensive methods of construction 20 are subject to rapid deterioration by loosening of parts, cracking and splintering.

The present invention embraces an all 25 metal spool comprising a tubular metallic barrel, with stamped metal heads made of integral disks, the interior or central portion of which is countersunk or cupped to form an annular shoulder adapted to fit inside the end of the metallic tube for attachment thereto and an axially projecting supporting journal for rotatably supporting the spool. To insure proper adhesion of the 30 yarn wound around the barrel, the latter is punched with a series of punched up projections which engage and hold the yarn 35 against slipping on the metallic surface of the barrel. Where the spools are intended for wide looms, they are made in longitudinal sections and in such case the intermediate spool journals are specially constructed to interlock two adjacent ends of the 40 spools or sections together to secure uniform rotation of all sections.

These and other features of my invention 45 will be described in this specification and will be defined in the claims hereto annexed.

In the accompanying drawings, I have illustrated a convenient and practical construction illustrating the principles of this invention, in which,

Fig. 1 is a front elevation partly in central section illustrating a yarn spool embodying the features of this invention.

Fig. 2 is a cross-section on plane X—X of Figure 1.

Fig. 3 is an end elevation of an inner end 55 of a spool section.

In the practice of this invention according to the form illustrated in the drawings I form the yarn carrying barrel of a sheet metal tube 1 of substantially cylindrical 60 shape and as the metallic surface affords insufficient adhesion to prevent slippage of the yarn being wound on the barrel, I provide it with exterior raised projections. In the form actually illustrated, a longitudinal metallic strip 3, arched to conform to the circumference of the barrel, is secured on the outer surface of the barrel after said strip has been punched out at frequent intervals to form numerous fine raised yarn engaging 70 and holding projections 2. The yarn retaining strip may be soldered, spot welded or otherwise attached to the barrel.

The end heads for the barrel are also made of metal and comprise essentially, in 75 each case, a circular disk 4 having its inner or central portion cupped or depressed to form an annular shoulder 4^a adapted to fit inside the open end of the barrel 1, to which it is fastened firmly by any suitable means as 80 by spot welding.

The central portion 4^a of each head forms a stiffening diaphragm in a plane parallel to but offset from the exteriorly projecting or peripheral yarn supporting portion of the 85 head.

The usual end supporting journal 6 is mounted centrally of the interior portion of the disk, but in cases where the yarn spool is made in axially aligned sections, the 90 inner end journal of the spool is made of a short length of tubing 5 whose larger end fits inside the offset annular flange 4^b to which it is firmly secured in any suitable manner, while the outwardly projecting reduced bearing part of the journal is 95 notched to form a series of axial projecting teeth arranged to engage a similarly notched journal of the adjacent spool so as to interlock therewith and insure uniform and equal

rotation of all spool sections. The notched or toothed ends lap by each other and rest in a common journal bearing when the yarn spool is mounted in the tube frame for use. To permit circumferential adjustment of the 100 spool sections the teeth 5^a and their alternating notches should be of equal width so that two such journals will intermatch when 105

brought together in different circumferential relationship.

The outside disks 4 are also shown as provided with outwardly turned peripheral flanges 4^c to give additional strength and stiffness to the structure besides affording sufficient peripheral surface to avoid cutting into the brake pads commonly used to retard the rotation of the spool in the tube frame as the yarn is drawn off.

What I claim is—

1. A yarn spool embracing a tubular barrel, opposite end heads comprising interiorly cupped disks, formed with annular shoulders adapted to fit inside the ends of the barrel and be secured thereto, the cupped interior portions of the disks being provided with axial projecting journals, one of which is provided with spaced teeth adapted to 20 interlock with a similar journal in another spool substantially as described.

2. A yarn spool embracing in its construction a tubular barrel circular and disks secured thereto to form yarn supporting flanges exteriorly of the spool, said disks having their central portions offset to form annular attaching shoulders adapted to fit inside the ends of the barrel and supporting journals projecting axially of said heads, 30 one of said journals comprising an annular member secured inside said annular shoulder and having its outer end notched to form

interlocking endwise engagement with an axial aligned spool substantially as described.

3. A yarn spool embracing a tubular barrel a supporting and stiffening head comprising a double flanged disk having an outwardly projecting peripheral flange and inwardly turned attaching flange dimensioned 40 to fit inside the end of the barrel for attachment thereto and a supporting journal comprising a stub shaft whose inner end is reduced to form a shoulder and passes centrally through said disk and is detachably 45 and rigidly clamped thereto, substantially as described.

4. A yarn-spool embracing in its construction a tubular barrel, a supporting and stiffening head comprising a double flanged 50 disk the inner flange of which is inwardly offset to form an attaching shoulder fitting inside the tubular barrel, and a tubular journal member whose inner end fits inside and is secured to said shoulder and 55 whose outwardly projecting portion is reduced in diameter and notched at its edge to form interlocking engagement with a similar journal member, substantially as described.

In witness whereof, I have subscribed to the above specification.

WALTER BIXBY.
